UNITED STATES PATENT OFFICE.

SAMUEL T. ADAMS, OF NEW BEDFORD, MASSACHUSETTS, ASSIGNOR TO THE
PAIRPOINT MANUFACTURING COMPANY, OF SAME PLACE.

DESIGN FOR A SPOON.

SPECIFICATION forming part of Design No. 21,107, dated October 13, 1891.

Application filed July 25, 1891. Serial No. 400,773. Term of patent 7 years.

To all whom it may concern:

Be it known that I, SAMUEL T. ADAMS, a citizen of the United States, residing at New Bedford, in the county of Bristol and State of Massachusetts, have invented a new and original Design for Handles for Spoons, &c., of which the following is a specification, reference being had to the accompanying drawing, forming part hereof and showing a handle 10 containing my new design.

The leading feature of my design consists in an unornamented field running from the butt-end of the handle toward the inner end thereof and parallel with an ornamented 15 field.

A minor feature of my design consists in the outline of the handle, as shown and described.

A is the unornamented field running lengthwise of the handle from its butt-end inwardly and extending laterally from one edge *a* of the handle to about the middle of the handle. B is the ornamented field extending lengthwise of the handle and extending laterally 25 from about the middle of the handle to the other edge *b* of the handle. These fields are in a sense parallel to each other. Of course one or both fields may be finished bright or satin, as desired, finish not being ornamenta-

tion in the sense here employed, as will be 30 plain from the drawing. The ornamentation of field B may be by raised or depressed figures or the like, so that there is a marked contrast between the two fields A and B. This leading feature of my design is preferably 35 embodied in a handle having the outline shown—that is, the handle is curved on its edges *a* and *b*, edge *a* being indented at *a'*, the butt-end *d* being rounded, indented at *d'* and *d''*, and forming a rounded termination 40 *b'* at the butt-end of edge *b*.

I claim—

The design for a handle for spoons herein shown and described, the same consisting in a plain curved field A, an ornamented field B, 45 edge *a* of the handle being indented at *a'*, the butt-end of the handle having a rounded projection *d* between indentation *a'*, and an indentation *d'* at the butt-end of the handle, which is also indented at *d''* to form a rounded projection *b'* on edge *b* near the butt-end of the handle, field A extending to the extreme end of the handle and curving as shown, all as shown.

SAMUEL T. ADAMS.
